[57] ABSTRACT

An automatic gain control circuit which includes an amplifier portion for amplifying the automatic gain control signal, an impedance control portion driven by the output of the amplifier portion, a variable impedance portion provided separately from the amplifier portion and controlled by the impedance control portion, and an AC bypass portion arranged on the input side of the impedance control portion, whereby even when the control signal is at a low level, the gain control can be effected at a low distortion factor.

FIG. 5

AUTOMATIC GAIN CONTROL CIRCUIT

BACKGROUND OF THE INVENTION

1. Field of the Invention

The present invention relates to an automatic gain control circuit, and more particularly to an automatic gain control circuit suitable for fabrication as an integrated semiconductor circuit.

2. Description of the Prior Art

As shown in FIG. 1, a conventional voice amplifier device is constructed such that a voice input signal supplied to an input terminal IN is amplified by a preamplifier portion A, and the amplified input signal is fed through a power amplifier portion PA to a speaker SP. In this case, a matching transformer T is arranged between the power amplifier portion PA and the speaker SP, so as to effect impedance matching between the amplifier and the speaker. In order to provide automatic gain control, an automatic gain control circuit AGC is arranged between the output side and the input side of the power amplifier portion PA. In the figure, R₁ and R₂ designate resistances, and T₁ - T₄ designate terminals of the automatic gain control circuit AGC.

The automatic gain control circuit AGC generally employed in the system of FIG. 1 is composed, as illustrated in FIG. 2, of an n-p-n transistor Q₁, and three diodes D₁ - D₃ which are connected in series in the forward direction to the emitter of the transistor Q₁. One end of the diode D₃ is grounded through the terminal T₄, while the collector of the transistor Q₁ is connected to a power source V_{cc} through the terminal T₁. Supplied through the terminal T₂ to the base of the transistor Q₁ is an automatic gain control signal S_{c1} which is produced in such a way that an AC signal derived from the output side of the power amplifier portion PA in FIG. 1 is rectified and smoothed by means of a detecting diode D₄ and a capacitor C₁. The juncture P₁ between the diodes D₁ and D₂ is connected through the terminal T₃ as well as a capacitor C₂ to the input side of the power amplifier portion PA.

Depending on the magnitude of the control signal S_{c1} supplied to the base of the transistor Q₁, the impedance of the diodes D₁ - D₃ varies, so that the impedance component included in the input of the power amplifier portion PA changes. Thus, the gain control of the device is carried out.

With such a construction, gain control is possible with a small control current. Furthermore, the input signal to be controlled is subject to push-pull operation, so that even-order higher harmonics are removed, making gain control with a low distortion factor possible. On the other hand, however, the voltage to be supplied to the base of the transistor Q₁ must be made higher than the sum of the rise voltages of the transistor Q₁ and the diodes D₁ - D₃ in order to reduce the distortion attributable to the non-linearity of the rise in the voltage-current characteristics of the transistor Q₁ and the diodes D₁ - D₃. In particular, since the transistor Q₁ also has the detecting diode D₄ connected on its input side, the effective voltage required for automatic gain control is approximately 3 V or higher.

For this reason, according to the prior art, a special winding for taking out the automatic gain control signal is provided on the secondary side of the matching transformer T disposed on the output side of the power amplifier portion PA.

When it is intended to utilize the automatic gain control circuit AGC of the foregoing construction with a voice amplifier device of the OTL system, the voltage for automatic gain control cannot be set to a high level, as a result of which the circuit is subjected to an increased distortion.

SUMMARY OF THE INVENTION

It is therefore a principal object of the present invention to provide an automatic gain control circuit which enables gain control with a low distortion factor even with a control signal of low level.

Another object of the present invention is to provide an automatic gain control circuit which is suitable to be provided in the form of an integrated semiconductor circuit.

In order to accomplish such objects, the present invention consists of a circuit in which an automatic gain control signal is amplified after detection. The amplifier portion therefor and a variable impedance portion are separated, the latter being controlled by an impedance control portion which is driven by the output of the amplifier portion.

BRIEF DESCRIPTION OF THE DRAWINGS

FIG. 1 is a schematic circuit diagram already referred to, showing an example of a prior-art voice amplifier device;

FIG. 2 is a schematic circuit diagram already referred to, showing an example of the automatic gain control circuit in FIG. 1; and

FIGS. 3 to 5 are schematic circuit diagrams each showing a respective embodiment of the automatic gain control circuit according to the present invention.

PREFERRED EMBODIMENTS OF THE INVENTION

FIG. 3 shows an embodiment of the automatic gain control circuit according to the present invention. In the figure, Q₃ - Q₇ designate n-p-n transistors, Q₈ and Q₉ designate p-n-p transistors, and R₃ designates a resistance. The transistor Q₃ constituting an amplifier portion for an automatic gain control signal has its emitter connected through the resistance R₃ to a terminal T₄ leading to ground, and has its collector connected through the collector and emitter of the transistor Q₈ to a power source terminal T₁. The base of the transistor Q₈ is connected to its collector electrode and to the base of the transistor Q₉. The emitter of the transistor Q₉ is connected to the power source terminal T₁, while the collector is connected to the base of the transistor Q₆ constituting an impedance control portion. The collector of the transistor Q₆ is connected to the power source terminal T₁, while the emitter is connected to a terminal T₃ (on the input side of the power amplifier portion in FIG. 1) and also to ground at the terminal T₄ through the collector-emitter junction of the transistor Q₇. The transistor Q₇ has its base connected to its collector, thus constituting a variable impedance diode. Further, the transistors Q₄ and Q₅ are connected in series with their respective bases connected to their collectors. Thus, they constitute AC bypass diodes. The collector of the transistor Q₄ is connected to the collector of the transistor Q₉, while the emitter of the transistor Q₅ is connected to ground at the terminal T₄.

With such a construction, the detected automatic gain control signal S_{C1} applied to the terminal T_2 (the input terminal of the automatic gain control circuit) is sufficiently DC-amplified by the transistor Q_3 . The amplified signal is applied through the transistors Q_8 and Q_9 to the base of the transistor Q_6 . Accordingly, a voltage sufficiently higher than the rise voltage V_F of the transistor Q_6 is applied to the transistor Q_7 which is connected on the emitter side of the transistor Q_6 and which constitutes a variable impedance diode. For this reason, the transistor Q_7 operates in an operating region of little non-linear distortion. In consequence, even if the automatic gain control signal S_{C1} applied to the terminal T_2 is at a low level, a gain control of low distortion factor can be effected.

Across the transistors Q_4 and Q_5 connected in series and respectively constituting the AC bypass diodes, there is applied a voltage which is higher than double the rise voltage V_F . The dynamic resistances of these transistors Q_4 and Q_5 are accordingly very small, so that the base of the transistor Q_6 for controlling the gain is grounded AC-wise. Consequently, the transistors Q_6 and Q_7 can effect a substantially perfect push-pull operation for the input signal to-be-controlled. For this reason, even if the automatic gain control signal is at a low input level, it is possible to achieve a low distortion factor.

With the construction of the present invention as described above, even though the detector portion including diode D_4 for detecting the signal derived from transformer T for automatic gain control and the impedance control portion formed by the transistor Q_6 are separated by the amplifier portion formed by transistor Q_3 , the previously required capacitor C_1 of the detector portion is not necessary since the AC bypass diodes composed of the transistors Q_4 and Q_5 are employed. Accordingly, if the automatic gain control circuit is constructed as an integrated semiconductor circuit (IC), terminals otherwise fitted outside the IC device for connecting such a capacitor are unnecessary, and therefore, the number of terminals required for external connection to the IC device need not be especially increased.

FIG. 4 shows another embodiment of the automatic gain control circuit according to the present invention. In this case, diodes D_5 and D_6 are employed in place of the transistor Q_7 in FIG. 3, and diodes D_7 - D_{10} are used in place of the transistors Q_4 and Q_5 . With such a construction, the rise of the voltage-current characteristic of the diodes D_5 and D_6 constituting variable impedance diodes becomes smaller than in the case of the circuit of FIG. 3. This results in less distortion.

Herein, a diode D_{11} is connected to the emitter side of the transistor Q_6 , so that, when the transistor Q_6 and the diodes D_5 and D_6 perform the push-pull operation for the input signal to-be-controlled, the impedances for the positive and negative cycles of the input signal to-be-controlled may be matched to reduce the distortion.

The four diodes D_7 - D_{10} constituting AC bypass diodes are employed so that the base of the transistor Q_6 can be grounded AC-wise by making the sum of the rise voltages of the transistor Q_6 and the diodes D_{11} , D_5 and D_6 and the sum of the rise voltages of the diodes D_7 - D_{10} substantially equal. The AC resistance of these diodes D_7 - D_{10} is selected to be sufficiently smaller than

the AC resistance of the transistor Q_6 and the diode D_{11} or that of the diodes D_5 and D_6 .

FIG. 5 shows still another embodiment of the automatic gain control circuit according to the present invention. In this case, a load resistance R_4 is substituted for the transistors Q_8 and Q_9 in FIG. 4. Even with such a construction, substantially the same operation as in the foregoing cases can be effected.

Although, in the embodiments described above, the bipolar transistor is employed as the impedance control portion, it may, of course, be replaced with a MOS field-effect transistor.

Although, in the embodiments, the transistors or usual diodes having rise voltages are used as the AC bypass portion, it may be constituted of any semiconductor device having a rise voltage. For example, a Zener diode may also be used. In this case, the semiconductor device should preferably have the lowest possible AC resistance in a region of voltages above the rise voltage.

Although, in the embodiments, the transistor or usual diodes having rise voltages are employed as the variable impedance portion as in the AC bypass portion referred to above, they may be replaced with any other semiconductor device having a rise voltage.

As described above, in accordance with the automatic gain control circuit of the present invention, a gain control of low distortion factor can be effected even for an automatic gain control signal of low level. Besides, when the present invention is applied to a voice amplifier device of, for example, the OTL system which employs an integrated semiconductor circuit, a capacitor between the automatic gain control circuit and the power amplifier portion can be dispensed with. It is therefore possible to decrease the number of terminals to be externally provided for the integrated circuit, and to obtain miniaturization of the device.

What is claimed is:

1. An automatic gain control circuit comprising amplifier means for amplifying an automatic gain control signal, variable impedance means having a non-linear voltage characteristic for providing a varying impedance in response to the amplified automatic gain control signal, an impedance control circuit connecting the output of said amplifier means to said variable impedance means, and bypass means including a plurality of forward biased PN junction devices series connected to the input of said impedance control circuit and having a non-linear voltage characteristic for bypassing AC signal components to ground.

2. An automatic gain control circuit as defined in claim 1, wherein said amplifier means includes a voltage source, a first transistor connected to said voltage source and having its input electrode connected to an input terminal receiving said automatic gain control signal.

3. An automatic gain control circuit as defined in claim 2, wherein said amplifier means further includes a second transistor connected between said first transistor and said impedance control circuit.

4. An automatic gain control circuit as defined in claim 2, wherein said amplifier means further includes a first resistor connected between said first transistor and said voltage source and a second resistor connected between said first transistor and ground.

5. An automatic gain control circuit as defined in claim 4, wherein said impedance control circuit in-

cludes a second transistor connected between said voltage source and an output terminal and having an input electrode connected to the output of said amplifier means.

6. An automatic gain control circuit as defined in claim 5, wherein said impedance control circuit further includes a diode connected between said second transistor and said output terminal.

7. An automatic gain control circuit as defined in claim 6, wherein said variable impedance means includes a first pair of diodes connected in series between said output terminal and ground.

8. An automatic gain control circuit as defined in claim 7, wherein said PN junction devices of said bypass means include second and third pairs of series connected diodes connected in series between the input electrode of said third transistor and ground.

9. An automatic gain control circuit as defined in claim 1, wherein said PN junction devices of said bypass means include a plurality of diodes connected in series between the input of said impedance control circuit and ground.

10. An automatic gain control circuit as defined in claim 1, wherein the number of PN junction devices provided in said bypass means is equal to the number of forward biased PN junctions comprised in said variable impedance means and said impedance control circuit.

11. An automatic gain control circuit comprising amplifier means for amplifying an automatic gain control signal, variable impedance means having a non-linear voltage characteristic for providing a varying impedance in response to the amplified automatic gain control signal, an impedance control circuit connecting the output of said amplifier means to said variable impedance means, and bypass means connected to the input

of said impedance control circuit and having a non-linear voltage characteristic for bypassing AC signal components to ground, wherein said impedance control circuit includes a first transistor connected between a voltage source and an output terminal and having an input electrode connected to the output of said amplifier means, said variable impedance means being connected to said output terminal in series with said impedance control circuit across said voltage source.

12. An automatic gain control circuit as defined in claim 11, wherein said impedance control circuit further includes a diode connected between said first transistor and said output terminal.

13. An automatic gain control circuit as defined in claim 11, wherein said variable impedance means includes a second transistor connected between said output terminal and ground, the base of said second transistor being connected to the collector thereof.

14. An automatic gain control circuit as defined in claim 13, wherein said bypass means includes third and fourth transistors connected in series and each having its base connected to its collector.

15. An automatic gain control circuit as defined in claim 11, wherein said variable impedance means includes a first pair of diodes connected in series between said output terminal and ground.

16. An automatic gain control circuit as defined in claim 15, wherein said bypass means includes second and third pairs of series connected diodes connected in series between the input electrode of said first transistor and ground.

17. An automatic gain control circuit as defined in claim 11, wherein said variable impedance means includes a first pair of diodes connected in series between said output terminal and ground.
